US00D594309S

(12) **United States Design Patent**
Sugiura et al.

(10) **Patent No.:** US D594,309 S
(45) **Date of Patent:** ** Jun. 16, 2009

(54) **UTILITY KNIFE**

(75) Inventors: **Takahiko Sugiura**, Kyoto (JP);
Katsuyuki Kondo, Otsu (JP)

(73) Assignee: **Muratec-KDS Corp.**, Kyoto-shi (JP)

(**) Term: **14 Years**

(21) Appl. No.: **29/309,502**

(22) Filed: **Aug. 25, 2008**

(30) **Foreign Application Priority Data**

Feb. 26, 2008 (JP) 2008-004299

(51) **LOC (9) Cl.** 08-03

(52) **U.S. Cl.** D8/99

(58) **Field of Classification Search** D8/98,
D8/99; 30/162, 320, 335, 336, 337, 125
See application file for complete search history.
